LOUIS FELLHEIMER, OF NEW YORK, N. Y.

Letters Patent No. 63,234, dated March 26, 1867.

IMPROVEMENT IN HOOP SKIRTS.

The Schedule referred to in these Letters Patent and making part of the same.

TO ALL WHOM IT MAY CONCERN:

Be it known that I, LOUIS FELLHEIMER, of the city, county, and State of New York, have invented a new and improved Hoop Skirt; and I do hereby declare that the following is a full, clear, and exact description thereof, which will enable others skilled in the art to make and use the same, reference being had to the accompanying drawings, forming a part of this specification, in which—

Figure 1, plate 1, represents a side view of a hoop skirt, as worn.

Figure 2, plate 2, represents a similar view.

Figure 3 is a front view of the hoop skirt, with an ordinary skirt attached thereto.

Figure 4 shows a view of a person with dress in full train.

The object of this invention is to provide a hoop skirt which will overcome the objection heretofore experienced by ladies on entering and leaving carriages from the entanglement of their feet in the skirts. Another object is to provide a hoop skirt which will fit either stout or slender females, which I accomplish by having a gathering on the rear end of the waist-band, through which passes a series of strings sewed or otherwise attached on each side of the gathering, to two separate strings, which are drawn around the waist and tied. On the upper inner side of the skirt, in opposite direction to each other, are sewed, or otherwise attached, bands, to which is fastened a series of strings, as shown in the drawings, fig. 1, plate 1, the object of which is to convert the skirt into a trailing form; this is accomplished by passing the strings around the rear of the ordinary skirt, and there securely tied.

A, in the drawings, represents a hoop skirt, the front part of which is cut away to enable the wearer to exercise with more safety while entering or leaving vehicles, etc.; this is accomplished by fastening the hoops on each side of the skirt to an upright stay, a' , the lower hoops b passing entirely around the skirt in order to give steadiness and strength. B represents a waist-band or belt, to the rear of which is attached a gathering, b' , through which pass strings, c , which, when drawn apart and passed around the waist and tied in front of the skirt, will accommodate itself to the wearer, whether she be stout or slender in form. C represents two small bands, which are attached in opposite directions to each other on the upper inner sides of the hoop skirt. To these bands is attached a series of strings, d , which terminate in two bands, d' ; by drawing these bands to rear and over the bustle of the skirts and there tied, the hoop skirt will be brought into a trailing position, as shown in the drawings, fig. 1, plate 1, and fig. 4, plate 2. The skirt may be made, as shown in figs. 1 and 2, with fluting or other ornament attached to bottom thereof, or an ordinary skirt sewn thereon, as shown in fig. 3, plate 2, of the drawings. The hoops in the skirt are so arranged that they can be easily removed, and replaced after the skirt has been washed.

Having thus described my invention, what I claim as new, and desire to secure by Letters Patent, is—

The skirt, with the lower hoops passing entirely around the skirt, and the upper ones secured to the stay a' , and provided with the gathering b' attached to the waist-band, and having at its rear the "trailing device," consisting of the bands C, strings d , and bands d' , when all parts are combined and arranged in the manner herein represented and described.

LOUIS FELLHEIMER.
